UNITED STATES PATENT OFFICE.

WILLIAM H. COOK, OF URBANA, OHIO, ASSIGNOR TO CHAUNCEY B. FORWARD, OF URBANA, OHIO.

HEAT EXCHANGER.

Application filed March 20, 1922. Serial No. 545,125.

To all whom it may concern:

Be it known that I, WILLIAM H. COOK, a citizen of the United States, residing at Urbana, in the county of Champaign and 5 State of Ohio, have invented certain new and useful Improvements in Heat Exchangers, of which the following is a specification.

This invention relates to heat exchangers 10 for transferring heat from one moving body of fluid to another and is particularly designed for use in oil refining systems, in which the oil being treated is heated by means of steam, oil vapor or heated oil at a 15 high temperature and pressure.

It is an object of the invention to construct the heat exchanger in a compact form in which a fluid conduit of great length is subjected to the heating fluid confined to 20 a path of travel along the exterior of the conduit. A further object is to minimize the loss of heat due to external radiation. Other objects will appear from the following description in connection with the annexed drawings.

The following description and annexed drawings set forth in detail certain means embodying the invention, the disclosed means, however constituting but one of the 30 various mechanical forms in which the principle of the invention may be employed.

In said annexed drawings:

Fig. 1 shows a central vertical section through the heat exchanger.

Fig. 2 is a view showing the exchanger partly in side elevation and partly in vertical section the walls of the cylinders being progressively broken away from the bottom towards the top to show the arrangement 40 of the pipe coils.

Fig. 3 shows a section taken on the plane indicated by line 3—3 in Fig. 1.

Fig. 4 is a fragmentary sectional view showing the connection between adjacent 45 pipe coils at the base of the casing.

Fig. 5 a sectional view taken on line 5—5 of Fig. 1.

Fig. 6 is a diagrammatic view showing the manner in which the pipe coils are connected to form a continuous conduit.

Referring to the drawings, the heat exchanger casing consists of a cylindrical metallic shell 1 formed from relatively heavy plate, a top plate 2 and a bottom plate 3.

55 The top plate 2 is bolted to a flanged ring

4 welded or otherwise fixed to the upper edge of the shell 1. A sheet of packing material 5 is clamped between the lower face of the plate 2 and the upper edge of the shell. The bottom 3 is bolted to a flanged 60 ring 6 similar to the ring 4 secured to the bottom of the shell 1 and a packing sheet 7, corresponding to the sheet 5 is secured between the plate 3 and bottom of the shell. Inside the shell 1 are a series of concentric 65 cylinders, clamped between the top and bottom plates 2 and 3. The inner cylinder 8 is of relatively small diameter the outermost of the inner cylinders 9 forms with the outer shell 1 an annular chamber 10. 70 Between the cylinders 8 and 9 are a series of intermediate cylinders 11 of regularly increasing diameter forming a series of annular chambers 12 all of the same radial width. An inlet pipe 13 is passed through 75 the base 3 into the outer annular chamber 10 and is formed into a coil 14 fitting the outer surface of the cylinder 9. The inner and outer cylinders 8 and 9 have openings 15 and 16 adjacent the top and alternate 80 intermediate cylinders 11 have similar openings 17 adjacent the top thereof. The alternate intermediate cylinders 11 between the cylinders having openings adjacent the tops thereof have openings 18 adjacent the bottoms thereof. The pipe 13 at the upper end of the coil 14 is bent inwardly through the opening 16 at the top of the cylinder 9 into the outermost of the annular chambers 12 where it is formed into a coil 19 the inclination 85 of the convolutions of which is reversed with respect to the convolutions of the coil 14. At the bottom of the outer of the chambers 12 the pipe 13' extends through the bottom plate 3 and has secured thereto 90 a T fitting 20 to which is attached a drain cock 21 and a short horizontal pipe section 22 connected through an elbow fitting 23 with the lower end of a pipe 24 which is coiled in the next two inner concentric chambers 12. The pipe 24 extends up through the base plate 3, is coiled in the second inner annular chamber, passes through the outer of the upper openings 17 and is reversely coiled in the third inner annular chamber. 95 Successive concentric coils are formed in the same manner inside the coils 14 and 19 until the inner annular chamber 12 is reached. The single pipe which forms two concentric coils 26 and 27 extends upwardly 100 105 110

in the inner of the annular chambers 12 and downwardly through cylinder 8 and the convolutions of coil 27 are disposed at a relatively steep angle owing to the small diameter of the cylinder 8. The connecting portion of coils 26 and 27 passes through the opening 15 at the top of the cylinder 8. The lower end 25 of coil 27 extends through the bottom plate 3 and is connected with a suitable discharge conduit. The pipes from which the concentric coils are formed are of an external diameter to fit tightly between the cylindrical walls of the annular chambers 12 in which they are located and may be spot welded or otherwise rigidly secured to said walls to form a fluid tight connection therewith. The outer annular chamber 10 is wider than the intermediate chambers 12 so that an open space is provided between the coil 14 and the shell 1. An inlet conduit 28 for the heating fluid, communicates through the bottom plate 3 with the interior of the cylinder 8, and an outlet conduit 29 for the heating fluid communicates with the outer annular chamber 10 through the bottom plate 3.

In operation the heating fluid, which may be steam at a high temperature and under high pressure, oil vapor, or other suitable heated fluid, passes into the inner cylinder 8 around the inner coil 27 on the interior of the cylinder 8, through the opening 15 into the inner of the annular chambers 12, through the helical passage formed in the inner annular chamber between the convolutions of the coil 26 to the bottom of the chamber, thence through the lower opening 18 into the next outer annular chamber thence through the helical passages in the successive annular chambers 12 communicating with each other through the openings 17 and 18 at the top and bottom of alternate cylinders 11, and finally into the outer annular chamber 10 through the opening 16 at the top of the cylinder 9, over the outer coil 14 and out through the outlet conduit 29. The oil or fluid to be heated enters pipe 13 into the outer coil 14 and passes upwardly through said coil which is subjected to the heating fluid from which the greater portion of the heat has been taken, thence successively through the concentric inner coils which are subjected to heating fluid of progressively higher temperatures, and finally through the interior coil 27 which is subjected to the incoming heating fluid delivered at high temperature into the interior cylinder 8 through the inlet conduit 28. The oil or fluid passes out of the discharge conduit 25 at substantially the temperature of the heating fluid.

The location of the heating fluid inlet 28 and the outlet 25 for the heated fluid at the center of the cylindrical casing concentrates the heat in the central portion of the ex-

changer whereby the loss of heat by external radiation is practically eliminated. As well understood in the art the exposed surfaces of the casing and conduits may be provided with suitable heat insulating coverings not shown. Drain pipes 30 extend through the bottom plate 3 into each of the annular chambers 12 and are provided with valves 31 whereby liquid condensing and settling in the bottoms of the chambers can be drawn off from time to time. The pipes 30 extend slightly above the bottom plate 3 so that a layer of liquid will remain in the bottoms of the annular chambers 12 below the openings 18 forming a liquid seal preventing leakage of vapor beneath the cylinders having closed bottom portions.

Each of the openings for the pipe terminals in bottom plate 3 is made fluid tight by packing held in place by packing glands 33. The fluid in the coils within the exchanger casing can be completely drained by means of the cocks 21 in the connections between the lower ends of the coils, it being understood that the pipe terminal of one coil passes through bottom plate 3 closely adjacent the terminal of the next coil as shown in Fig. 5 to permit convenient assembly and connection as shown in Fig. 4.

What I claim, is:

1. In a heat exchanger, a continuous conduit consisting of a large number of concentrically disposed helical pipe coils confined within a closed chamber; and a series of concentric cylinders engaging said pipes and forming closed, helical fluid passages exteriorly of said pipe following the convolutions of said coils.

2. In a heat exchanger, an outer cylindrical casing having a fluid tight top and bottom, a series of concentric cylinders within said outer casing extending from the bottom to the top thereof, helical pipe coils in the annular spaces between successive cylinders said coils being formed of pipe of a size to fit between the walls of the concentric cylinders, said coils in successive annular spaces having an opposite inclination; said coils being connected end to end to form a continuous passage, said inner cylinders having openings alternately at the top and bottom thereof whereby a passage for fluid is formed exteriorly of said coils and co-extensive therewith.

3. In a heat exchanger, an outer casing, a continuous conduit therein formed by a series of interconnected concentric helical coils, cylindrical partition members interposed between the successive concentric coils and fitting tightly thereagainst to provide closed spiral steam passages paralleling the convolutions of each coil; inlet and outlet conduits connected to the bottom ends of said outer and inner coils respectively; inlet and outlet passages for a heated fluid con-

nected to said casing within said inner coil and outside said outer coil respectively said partition members having openings alternately in the tops and bottoms thereof.

5. In a heat exchanger an outer casing comprising a cylindrical shell and a base and top having a fluid tight connection therewith, an inner concentric cylinder having a fluid tight connection with said base and top; and a series of concentrically disposed cylinders surrounding said inner cylinder a helical pipe coil in said inner cylinder an oppositely inclined coil connected with said inner coil other inter-connected concentric coils in the annular spaces between successive cylinders, the pipe of the coils being of a diameter to fit tightly in the space between successive cylinders whereby helical passages are formed between the convolutions of the coils, said cylinders having openings establishing communication between the ends of helical passages formed along successive concentric coils.

25. In a heat exchanger, an outer casing, a series of concentric helical coils therein forming a continuous passage for fluid to be heated, means for conducting a heating fluid along a continuous passage following the convolutions of said coils; means for 30 draining the individual coils; and means for passing said heating fluid and fluid to be heated in opposite directions through said passages.

35. In a heat exchanger, an outer casing, a series of concentric helical pipe coils therein forming a continuous passage for fluid to be heated, concentric partition members closely engaging said pipe coils, forming with said coils concentric helical 40 passages for a heating fluid, said partition members having openings adjacent their tops and bottoms alternately whereby said helical passages are connected to form a continuous closed spiral passage for heating fluid along the exterior of the coiled pipe.

45. In a heat exchanger, an outer casing comprising a cylindrical wall a base and top having a fluid tight connection therewith, a large number of inner concentric cylinders having a fluid tight connection with said base and top, a conduit for fluid to be heated comprising a series of concentric coils disposed in the spaces between and 50 engaged with the walls of successive concentric cylinders, said cylinders having openings alternately in the tops and bottoms thereof, successive pairs of coils having connecting portions extending through the top openings, means for admitting heating fluid to said central cylinder, and an outlet for said heating fluid communicating with the outer annular chamber.

55. In a heat exchanger, an outer casing comprising a cylindrical wall a base and

top having a fluid tight connection therewith, a series of concentric cylinders having a fluid tight connection with said base and top forming annular inner chambers, said annular chambers being in communication at the top and bottom, respectively with adjoining chambers an outlet for the heating fluid communicating with the outer annular chamber, a separate drain for each of said annular chambers, and a passage for fluid to be heated consisting of a series of connected concentric coils disposed in said annular chambers.

60. In a heat exchanger, an outer casing comprising a cylindrical shell and a base and top having a fluid tight connection therewith, a series of concentric inner cylinders having fluid tight connections with said base and top and forming between them a series of annular concentric chambers, each chamber having openings adjacent its bottom and top, respectively, to adjacent annular chambers, drain pipes for each of said inner annular chambers said drain pipes projecting above the base whereby a liquid seal is provided at the bottom of the casing, and a passage for fluid to be heated consisting of interconnected concentrically disposed helical pipe coils disposed in said annular chambers.

65. In a heat exchanger, an outer casing consisting of a cylindrical shell and a base and a top having fluid tight connections therewith, a series of concentric inner cylinders having fluid tight connections with said base and top and forming between them a series of annular concentric chambers, said cylinders having openings alternately at the top and bottoms thereof, an inlet for heating fluid communicating through the base with the inner of said cylinders, an outlet for heating fluid communicating with the outer annular chamber, and a conduit for fluid to be heated having its inlet end extending through the base from said outer annular chamber, its discharge end projecting through the base within said inner cylinder and its intermediate portion consisting of interconnected concentric helical coils of pipe disposed in said annular chambers, the pipe at the upper ends of the coils extending inwardly through the openings at top of the cylinders and inclined reversely in the next adjacent coil; and means including a drain cock for connecting the lower ends of adjacent coils.

70. In a heat exchanger, an outer cylindrical casing, a pipe conduit for fluid to be heated in said casing, comprising a large number of coils of different diameter concentrically arranged, said conduit having its inlet at the end of the outer coil and its outlet at the end of the inner coil, concentric cylinders confining each concentric coil

of pipe closely to provide a closed tortuous passage for a heating fluid, said heating fluid passage having its top and bottom portions formed by the pipes and following the convolutions of said coils, an inlet for said heating fluid communicating with the interior of the central cylinder and an out-

let for said heating fluid communicating with the space between the outer cylinder and the casing adjacent said outer coil.

WILLIAM H. COOK.
